UNITED STATES PATENT OFFICE.

ERNST H. HUENEFELD, OF CINCINNATI, OHIO.

DESIGN FOR A HEATING-STOVE.

SPECIFICATION forming part of Design No. 31,013, dated June 13, 1899.

Application filed May 9, 1899. Serial No. 716,176. Term of patent 14 years.

To all whom it may concern:

Be it known that I, ERNST H. HUENEFELD, of Cincinnati, in the county of Hamilton and State of Ohio, have invented a new and original Design for Heating-Stoves, of which the following is a full, clear, and exact description, reference being had to the accompanying drawings, forming a part thereof.

In the accompanying drawings, Figure 1 is a view in side elevation of a stove embodying my design. Fig. 2 is a front view thereof, and Fig. 3 is a plan view.

The leading feature of my design consists of a stove-body oval or elongated in horizontal cross-section and mounted on legs, the top of the latter conforming to the external curvature of the body of the stove and overlapping the lower edge of the body, the oval or elongated body having a frame rectangular vertically when viewed from the front and sides projecting from the front thereof.

A represents the oval stove-body, provided near its upper and lower ends with corrugations or beads b and on its front with a projecting frame B, open in front, and which in front elevation is rectangular horizontally and is approximately rectangular vertically when viewed from the side. This oval body is mounted on legs B', the upper ends of which overlap the lower end of the oval body. Projecting from the top of the body and near the front thereof is a cylindrical collar C, surrounded by a conical cap D.

What I claim is—

The design for a heating-stove shown and described.

ERNST H. HUENEFELD.
